UNITED STATES PATENT OFFICE.

GEORGE B. BOARDMAN, OF CHICAGO, ILLINOIS.

COVERING FOR BOILERS.

SPECIFICATION forming part of Letters Patent No. 402,798, dated May 7, 1889.

Application filed January 15, 1889. Serial No. 296,443. (No model.)

To all whom it may concern:

Be it known that I, GEORGE B. BOARDMAN, a citizen of the United States, residing at Chicago, in the county of Cook and State of Illinois, have invented a new and useful Improvement in Non-Conducting Coverings for Boilers, Pipes, &c., of which the following is a specification.

My invention relates to an improved construction of the covering used for steam boilers, pipes, and other heated surfaces, to prevent the loss therefrom of heat by radiation, and for protecting gas and liquid pipes and the like from cold.

So far as I am aware, generally speaking, the various coverings hitherto invented for the same purpose as my improvement, when once applied to the surfaces they are designed to protect, cannot be readily removed nor without injuring them.

One of the more important objects of my improved construction of covering is to permit ready application thereof to its purpose, and as ready removal without thereby affecting it injuriously.

My invention is particularly designed to afford an improvement upon a construction of boiler and pipe covering at present in use, wherein sections or "boxes" formed of asbestos paper are filled with mineral wool and applied to the surface to be covered, being cemented together by means, ordinarily, of silicate of soda, the covering to protect it against injury being shielded while in use by winding canvas or the like around it, or, as in the case of locomotive-boilers, by incasing it in a shield of sheet metal. While this construction of covering affords many advantages, the filling of mineral wool, which is a somewhat fluffy material, tends to settle and pack particularly by the jarring of machinery on or near which the covering is applied, and thus undesirable spaces are produced in the filling, and the covering cannot, readily at least, be removed without injuring or destroying the asbestos paper. In this connection my object is to provide a construction of covering formed with mineral wool or analogous substance non-conductive of heat or cold and liable to settle, whereby no settling or pack-

ing of the material in use shall take place, and which can be removed and reapplied as often as desired without injuring it.

To these ends my invention consists in a covering for steam boilers, pipes, and the like, comprising a sheet formed of a woven-wire back having the non-conducting material upon it and secured in place by strands of the wire; and it further consists in details of construction and combinations of parts. 60

In the accompanying drawings, Figure 1 is a plan view of a strip of my improved covering, showing at the ends thereof the woven wire upon and by which it is secured; and Fig. 2 is a section taken on the line 2 2 of Fig. 1, 65 and viewed in the direction of the arrows.

A denotes a sheet of my improved covering, which comprises a back, B, of woven wire, having secured to it a facing of material non-conductive of heat, preferably mineral wool C. 70 I prefer, though it is not necessary to do so, to secure the material C to the back in the weaving of the latter, when it is desirable to apply the material in oblong rectangular, or substantially rectangular, sections r, of a 75 length corresponding more or less accurately with the width of the wiresheet being woven, and to secure each section in place by passing over it at desired intervals across the sheet warp-wires w, which, if the material be 80 mineral wool, will become embedded in it; hence the dotted lines indicating the warp-wires in Fig. 1.

To permit the operation to be performed in the manner described, I impose upon the 85 partly-woven wire-cloth, one after another, blocks r of the material C, packed in rectangular oblong boxes, and as each box is thus imposed the desired number of warp-wires is passed over it and down and up through the 90 woof w' and over the next box subsequently imposed adjacent to the first, the latter being first withdrawn, which operations are repeated until the entire length of a sheet of my improved material has been produced. Of 95 course, however, the construction may be otherwise produced, as by stitching warp-wires by hand through the superimposed non-conducting material, which also, instead of being imposed in sections, may constitute a con- 100

tinuous layer. The construction described as it is illustrated, however, is preferred as affording the greatest advantages.

The ends of the warp-wires, which are pur-
5 posely intended to extend beyond the ex-
tremities of the superimposed non-conduct-
ing material, serve by twisting them together
from the ends which are brought adjacent to
each other in covering a surface to fasten the
10 ends of the sheet together; and while this
means of fastening affords perfect security it
is readily manipulated to unfasten and re-
fasten it as often as desired for removing and
replacing the covering without injury to the
15 latter.

Obviously, instead of using the warp-wires
w for securing the material *C* in place, the
woof-wires *w'* could be employed for the pur-
pose.

20 The construction renders the material *C*
practically integral with its sustaining me-
dium *B*, and thus prevents any possibility of
its settling and becoming packed in use.

What I claim as new, and desire to secure
25 by Letters Patent, is—

1. A covering for steam boilers, pipes, and
the like, comprising a sheet, *A*, formed of a

woven-wire back having non-conducting ma-
terial secured upon it by strands of the sheet
of woven wire, substantially as described.

30

2. A covering for steam boilers, pipes, and
the like, comprising a sheet, *A*, formed of a
woven-wire back having non-conducting ma-
terial secured upon it by strands of the sheet
of woven wire, and the ends of strands ex-
35 tending at opposite extremities of the sheet
beyond the superimposed non-conductive ma-
terial and affording fastening means, sub-
stantially as described.

35

3. A covering for steam boilers, pipes, and
the like, comprising a sheet, *A*, formed of a
woven-wire back, *B*, having mineral wool, *C*,
secured upon it by strands of the woven wire
forming the back, substantially as described.

40

4. A covering for steam boilers, pipes, and
the like, comprising a sheet, *A*, formed of a
woven-wire back, *B*, having sections *r* of
mineral wool, *C*, secured upon it by strands of
the woven wire forming the back, substan-
tially as described.
